LINE FINDER FOR TOLL BILLER

Ronald D. Dodge, Poughkeepsie, and Leon E. Palmer, Wappingers Falls, N. Y., assignors to International Business Machines Corporation, New York, N. Y., a corporation of New York

Application April 9, 1953, Serial No. 347,783

2 Claims. (Cl. 197—133)

This invention relates generally to typewriters, and more particularly, to a structure for automatically and adjustably controlling the length of a typing field.

In order to explain the operating principles of this invention, reference is made to a toll billing typewriter which is one of that class used for printing charges on conventional, long-distance telephone toll bills.

Toll bills are normally supplied in continuous strip form with perforations separating one bill from a succeeding one. The supply of blank bills is maintained usually as a stack of folded sheets located behind the typewriter so that the typist need no worry about inserting the blank bill forms, but need simply copy information onto the toll bills.

Unfortunately, the typist occasionally may forget and exceed the length of writing space or typing field allocated on the blank bills. To prevent this, and to simplify the typing of toll bills, it is an object of this invention to provide an improved structure for aligning a toll bill so that its first imprint line will automatically be positioned for typing.

It is a further object of this invention to provide a structure for signalling the typist that she has completed the last line of imprint or end of typing field of a toll bill.

It is a still further object of this invention to provide an improved mechanism for locking the keys of a typewriter after the last line of a predetermined field has been printed.

It is a still further object of this invention to provide a structure which simultaneously controls the positioning of a toll bill for the first line of imprint, and which facilitates the tearing of one bill from a strip.

Other objects of the invention will be pointed out in the following description and claims and illustrated in the accompanying drawings, which disclose, by way of example, the principle of the invention and the best mode, which has been contemplated, of applying that principle.

Briefly, this invention relates to an improved typewriter structure, wherein a pair of parallel rings are mounted on one end of a typewriter platen and coaxially thereof; each ring having a detent therein for conditioning mechanisms that control respectively, the limitation of manual rotation of the platen and the locking of the typewriter keyboard.

In the drawings:

Fig. 1 is a front view, partly in section, showing a typewriter carriage and platen mechanism.

Fig. 2 is a sectional view taken through the plane 2—2 of Fig. 1 in the direction of the arrows.

Fig. 3 is a plan view of a standard toll bill.

Fig. 4 is a sectional view taken through the plane 4—4 of Fig. 1, in the direction of the arrows.

Referring to the drawings, a typewriter carriage 1 is shown mounted for axial movement in a pair of guide rails 2 which, in turn, are supported by the typewriter base (not shown). A platen 3 is mounted for rotation in a pair of side supports 4 which are rigidly secured to

2

the carriage 1. The platen has a ratchet wheel 5 which cooperates with a line spacing mechanism, hereinafter described, to control the feeding of a work sheet past a printing line. A pair of parallel rings 6 and 7 are secured to and rotatable with ratchet wheel 5 and they condition, respectively, as will be hereinafter described, the positioning of a toll bill for the first line of printing, and the locking of the typewriter keyboard after the last line of printing.

10 In Fig. 3, a conventional toll bill 8 is shown. The bill has a length equal to the periphery of the platen 3, and the bill has a typing field extending from the line marked "start" to the line marked "stop." To condition the typewriter so that the predetermined typing field is readily ascertainable, ring 6 is provided with a detent or notch 9 which is positioned to align the toll bill for the first line of imprint or "start" line, while ring 7 is provided with a detent 10 which effects the locking of the keyboard when the last or "stop" line reaches printing position.

15 In order to explain the operation of the rings 6, 7 and their notches or detents 9, 10, respectively, reference is made to Figs. 1 and 2 of the drawings wherein a pawl or dog 11 is shown pivotally mounted on the side support 4 of the carriage 1 in alignment with ring 6, while a rocker arm 15 is shown pivotally mounted on the side support 4 in alignment with ring 7. The latter has a free end 16 engageable with detent 10.

20 In the position shown, the nose 12 of dog 11 is abutting a wall 13 of notch 9 thereby limiting the manual clockwise rotation (Fig. 2) of ring 6. Ring 6, however, is rigidly connected by any suitable means (not shown) with ratchet wheel 5 and both members are provided with an internal gear portion 17 driven by a gear 18 splined, as by pin 19, to a shaft 20. By pressing on a clutch button 21 at the outer end of the shaft, the latter is moved axially in opposition to a spring 22 for disengaging the gear 18 from the internal gear 17. Platen 3 and the shaft 20 then can be rotated relative to both the ring 6 and ratchet wheel 5 to vary the position of the work sheet and hence the position of the "start" line of toll bill 8 relative to detent 9. Upon release of the button 21, gear 18 again engages gear 17 for direct drive, and since the platen has a circumference equal to the length of the toll bill, all succeeding toll bills will be positioned for typing on the "start" line when dog 11 engages notch 9.

25 While the structure of dog 11 and detent 9 prevents manual rotation of the platen, the dog is lifted upon returning the carriage to start a new line and the platen is free at that time for a line spacing operation.

30 In order to describe this action, however, reference is made to the specific operation of the carriage return and line spacing mechanisms explained in detail in United States Patent 1,957,322 to C. W. Crumrine. As shown in this patent, a mechanism is provided for exerting a pull on a tape 23 (Fig. 1) for effecting a return of the carriage to its starting position. The tape 23 is connected to a bellcrank 24 mounted on a stud 25 supported by the carriage. A rocking of the bellcrank by a pull on the tape 23 causes an arm 26 of the bellcrank to exert a vertically downward pull on a pin 27, which in turn pulls down bracket 28 (Fig. 4). The motion of the latter is guided by the interaction of pins 29 with elongated slots 30, and, as described in the aforementioned U. S. patent, the downward motion of bracket 28 causes a pawl 31 to be cammed outwardly into engagement with the teeth of ratchet wheel 5 to rotate the same one, two or three line spaces in a manner well understood in the typewriter art.

35 The rocking of bellcrank arm 24 by the tension of tape 23 is also used to release pawl 11 from detent 9.

Specifically, a link 32 is employed to connect a pin 33 of crank arm 26 to pawl 11. In Fig. 2, link 32 is shown connected to the tail 34 of dog 11 by means of a pin 35 engaging an elongated slot 36. Rotation of arm 26 exerts a downward pull on link 32 to pivot dog 11 about its supporting stud 37 and thereby lift nose 12 out of notch 9. Since the line spacing operation above described takes place with the rotation of arm 26, detent 9 will be rotated out from under nose 12 and the latter will ride on the periphery of ring 6 for a revolution until detent 9 is again in alignment with nose 12.

It will be noted that since the toll bills are in strip form separated by transverse perforations, a longitudinal pull on a bill 8 will result in a tearing along the perforated, separating line when the manual rotation of platen 3 is suddenly halted by the action of pawl 11 falling into detent 9.

It should be noted too that because of the elongated slot 36, successive operation of the line spacing mechanism will not be impaired by pawl 11. The elongated slot permits pin 35 to ride upwardly so that link 32 and arm 26 can return to their rest position shown in Fig. 1 after each line spacing operation.

It has been mentioned that the interaction of rocker arm 15 and detent 10 brings about a locking of the typewriter keyboard after the bill "stop" line has been typed. This locking is effected in the following manner.

After pawl 11 has been raised out of detent 9, successive movements of the carriage to starting position after each line is typed, causes a line spacing operation and advancement of the work sheet. Simultaneously, ring 7 (which is shown in Fig. 1 as being concentric with and locked to ring 6 by means of set screw 39) is rotated with the platen.

Through this operation, detent 10 eventually rotates into engagement with the free end of the rocker arm 15. The latter is spring biased into engagement with the periphery of ring 7 to enter detent 10 when it is in position. Specifically, arm 15 is pivotally mounted on pin 38 supported by side bracket 4. A second arm 40, integral with arm 15 has a pin 43 supporting a bar 44 which, in turn, is connected to a pin 45 in an arm 46. Arm 46 is mounted for rotation about a stud 47 and it is held biased counterclockwise (Fig. 2) by means of a spring 48 which interconnects the upper end of arm 46 with a bracket 49.

Spring 48 produces a tension on bar 44 which, through pin 43, tends to rotate rocker arm 15 about its pivot 38 so that its free end is pressed against the peripheral surface of ring 7. Accordingly, when notch 10 overlies the free end, the latter will be forced by spring 48 into the notch 10. When this occurs, arm 46 is released for slightly further counterclockwise rotation about stud 47, whereupon its outer end 49 rotates a bail 50 which is pivotally positioned by means of a pair of pins 51 held by the brackets 4. Clockwise rotation of the bail 50 effects the rotation of the rocker arm 52 about its pivot pin 53, whereupon a rod 54, connected to the outer end of arm 52, is pushed forward, causing the keyboard lock bar 55 to be rotated counterclockwise about pivot 56 and in opposition to the spring 57 until its nose 58 is under the hook 59 in each of the key bars 60. Specifically, the lock bar extends transversely across all the key bars 60, and therefore, it locks all of them—including carriage return—to prevent operation of the typewriter while the rocker arm 15 is in the detent 10.

The detent 10 is of such a peripheral length, however, that it effects the locking of the keyboard for only one line of typing. This signals the operator that she has

come to the end of the allocated typing field on the toll bill, and she must then rotate the platen by hand or pull on the toll bill to rotate the platen and thus cam the rocker arm 15 out of the detent 10. As soon as the platen has been rotated manually one line, the keyboard is released and the typist can imprint the bill totals, if she so desires.

An incidental advantage of the construction of ring 7 lies in the simplicity of its adjustment. That is, by releasing set screw 39, ring 7 can be rotated relative to ring 6 and consequently the position of the "stop" line can be controlled to agree with the type bill form that is used.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In combination with a typewriter having a carriage, a platen, printing means, and line spacing mechanism, a start control mounted on said carriage for interrupting the manual rotation of said platen comprising a start ring having a notch therein, means mounting said ring on said platen for coaxial rotation therewith, and releasable means mounted on said carriage for engaging said notch to prevent rotation of said platen after every revolution thereof until said releasable means has been lifted out of said notch, said releasable means comprising a pawl pivotally mounted on said carriage, spring means biasing the nose of said pawl into peripheral contact with said start ring, and a linkage interconnecting said line spacing mechanism with said pawl to lift the same out of engagement with said start ring notch upon operation of said line spacing mechanism.

2. In combination with a typewriter having a carriage, a platen, key actuated printing means, and a line spacing mechanism, a start control for limiting the manual rotation of said platen and a stop control for locking said key actuated printing means, said start control comprising a start ring having a peripheral notch therein, means mounting the same on said platen for coaxial rotation therewith, a cooperating pawl mounted on said carriage for engagement with said start ring notch in one position of rotation of said platen thereby to limit the manual rotation thereof, said start control further including means conditioned by the operation of said line spacing mechanism to lift said pawl from said start ring notch to release said platen for manual rotation, said stop control comprising a stop ring having a peripheral notch therein, means mounting the same on said platen for coaxial rotation therewith, a rocker arm mounted on said carriage for engagement with said stop ring notch, resilient means biasing said rocker arm into peripheral contact with said stop ring, and means responsive to the engagement of said rocker arm with said stop ring notch for locking said key actuated printing means.
